UNITED STATES PATENT OFFICE

PERCIVAL S. TICE, OF CHICAGO, ILLINOIS, ASSIGNOR TO STEWART-WARNER CORPORATION, OF CHICAGO, ILLINOIS, A CORPORATION OF VIRGINIA

ELECTROMAGNETIC FUEL PUMP

Original application filed February 13, 1928, Serial No. 253,974. Divided and this application filed December 5, 1929. Serial No. 411,801.

This application is a division of my co-pending application for patent on electromagnetic fuel pump, Serial No. 253,974, filed February 13, 1928. The purpose of this invention is to provide an improved construction for feeding fuel from low level source to the carburetor of an internal combustion engine, the same comprising an electromagnetic pumping device. It consists in the elements and features of construction shown and described as indicated in the claims.

In the drawings:—

Figure 1 is a diagrammatic view showing an installation of the invention.

Figure 2 is a vertical section axial with respect to the cylinder of a form of electromagnetic pumping device embodying the invention designed and adapted to be installed submerged in the main tank from which the fuel is to be pumped for supplying the carburetor.

Figure 3 is a section at the line 3—3 on Figure 2.

Figure 4 is a section at the line 4—4 on Figure 2.

Figure 5 is a detail section at the line 5—5 on Figure 2.

Figure 6 is a section at the line 6—6 on Figure 1 and Figure 7.

Figure 7 is a section at the line 7—7 on Figure 6.

Referring to the drawings:

The carburetor of the engine to be served is seen at A; the main fuel tank usually carried at the rear of the vehicle to be served is seen at B; the pumping device in its entirety is indicated at C, where it is seen submerged in the fuel in the tank, B, and connected by a pipe, 10, leading out of the top of the tank with a pipe, 11, for conducting the fuel to a local fuel container, 12, of small capacity, mounted in proximity to the engine as at the front of the dash and under the cowl, and connected by the pipe, 13, for delivering the fuel by gravity to the carburetor.

In this installation the governing switch device indicated in its entirety on Figure 50 1 by reference letter, D, is mounted on the

container, 12, hereinafter more particularly identified as consisting of a casing, 90, having chambers, 91 and 98, for containing a limited quantity of fuel pumped thereto.

The construction of the pumping device will first be described in detail. It is of the general character of an electromagnetic pump in which the electromagnetic elements are of quasi solenoid type; that is, the iron core, 40, encompassed by the circuit windings, 41, 41, is hollow, and the armature element, 42, is adapted to telescope with the hollow core which has its ends fitted with pole pieces, 43, 43, between which the armature element, 42, has a short range of reciprocation in the tubular core, 40, which serves also as a pump barrel or cylinder in which the armature element, 42, operates as a piston, being suitably provided with packing rings as indicated at 44.

The pole pieces, 43, 43, are each apertured as seen at 43^a, for flow of the fuel pumped into and out of the cavities, 45, 45, by the armature acting as a piston and reciprocating the short distance shown consisting of the excess of length of the interval between the pole pieces over the length of the armature piston.

Guided in the pole pieces is an axially positioned rod, 46, on which the armature piston is mounted, and about this axial guide, as it may be called, of the armature piston, there are coiled springs, 47, 47, which are accommodated at the opposite ends in axial recesses, 42^b, 42^b, in the piston armature, said springs reacting between the bottoms of these recesses and the pole pieces respectively, tending to position the armature piston equidistantly between the two pole pieces, and so tending to return it to this position

when the pole piece which has attracted it in one direction, compressing the spring at that side, is de-energized by the interruption of the current through the circuit winding at that end of the magnet. The tubular core member, 40, is adapted for retaining the circuit windings by having fitted securely on it midway in its length an iron annular disk,

48, forming a spool head between the two windings; and similar iron spool heads, 48^a, 100

85

90

95

48^a, are securely fitted on the opposite outer ends of the pole pieces, 43, 43.

The entire electro-magnet assembly as thus described is encompassed by a sleeve, 49, 5 which is fitted snugly to the spool heads, 48, 48^a, 48^a, and at the right hand end (referring to Figure 2) there is secured an insulating disk, 50, upon which is mounted a "snap over" switch member, 51, hereinafter more 10 particularly described, which is operated by the thrust of the rod, 46, upon the movement of the armature piston under the alternating attraction of the opposite pole pieces, for shifting the current back and forth between 15 the two circuit windings, to cause said alternating attraction. The assembly encompassed and made securely unitary by the sleeve, 49, is enclosed in a casing, 60, in which it is fitted so as to partition the main, 20 cavity of the casing from the two cavities, 45, 45, from which the pipe, 10, leads for conducting the fuel in its way to the carbureter above described.

It may be understood that the entire pump 25 structure as seen in Figure 2 being submerged in the main tank derives fuel supply through a filter screen, 64, mounted on an annular bottom flange, 65, of the casing, 60, and enclosing an entrance chamber, 61, from 30 which the fuel is drawn alternately into the cavities, 45, 45, by the alternating strokes of the piston member, 42, the fuel entering past check valves, 67, 67, and being discharged from the cavities, 45, 45, respectively, past 35 check valves 68 and 69 (see Figure 3) into the passage, 62, formed in a boss, 66, at the upper side of the casing, 60, from which passage, 62, the pipe, 10, leads to the carbureter.

The snap switch will now be described in 40 detail in its relation to the parts of the circuit which it connects. A conductor, 70, leads from the engine ignition switch, not shown, through the governing switch, D, hereinafter described, and into and through 45 the pipe, 10, into the chamber, 62, and there-in to a binding post, 71, mounted in the partition wall, 169, at the inner side of which in the chamber, 62, said binding post is in contact with the resilient tongue, 72, of a bracket, 50 73, which is mounted on the insulating disk, 50. To this bracket the snap lever, 51, is pivoted at its upper end, said snap lever being forked at the lower end for carrying at that end a roller, 74, one end of which obtains its journal bearing in an elongated slot, 75, in one of the fork arms, 76, its journal bearing at the other end in the other fork arm being loose to permit the first mentioned end to play in the slot without cramping the bearing at the opposite end; and a stretched 55 spring, 77, connects the first mentioned end of the roller with the pivot of the lever at its upper end to the bracket as mentioned. The rod, 46, carries a conoidal cam collar, 78, 60 formed tapering from the maximum diam- 65

eter midway of its length, narrowing toward both ends. This cam collar is mounted on the rod, 46, at such position that midway in the stroke of the piston, 42, said cam collar stands with the plane of its maximum diameter containing the axis of the pivot of the lever, 51; and the length of said lever from its pivot at the upper end to the mounting of the roller, 74, at its lower end is such that the spring, 77, operates to hold the roller stressed upwardly against the cam collar.

Upon considering this construction it will be understood that when the rod carrying the double cone cam collar, 78, is thrust by the armature piston from one extreme position to the other, in passing the midway position it will force the roller against the resistance of the stretched spring outward from the axis of the cone, and upon the reaction of the spring pulling it back against the slope of the cone the lever will be swung in the opposite direction from the thrust of the rod. On the insulating disk, 50, there are mounted so as to project at opposite sides of the lever, 51, spring contacts, 80 and 81, which are connected respectively by circuit wires, 82 and 83, with the outer coils of the windings, 41 and 41, said windings having their innermost coils grounded by their connection to the core.

It will be seen from this construction that the thrust of the armature piston upon its attraction by one of the magnet pole pieces upon the energizing of that pole piece, by the current through its winding will cause the operation of the snap switch to shift the current to the other winding, energizing the opposite pole piece which will thereupon retract the armature piston, again reversing the connection, and thus the reciprocation of the armature piston will continue, and the pumping action will continue, pumping the fuel, until by any means, or from any cause, either the resistance of the fuel to the pumping action exceeds the pumping capacity of the device, or the energizing circuit is interrupted otherwise than in the alternating manner described which causes the reciprocation.

The intent of the structure being to maintain the pumping action in such manner as to maintain the supply of fuel to the carbureter and to interrupt the pumping action when the supply exceeds the carbureter requirements in the least degree, provision is made for interrupting the circuit by the action of the fuel pumped when the supply passes the predetermined limit of the requirement of the carbureter. This interruption of the circuit is effected by the governing device which will now be described.

The governing device, indicated in totality by reference letter, D includes the casing, 90, and particularly the chamber, 91, therein, the outer side wall of which comprises a flexible diaphragm, 92, stressed inwardly by an ex-

terior spring, 93, reacting at its outer end against a spider or bridge member, 90^a, mounted exteriorly on the casing. Binding posts, 96 and 96^a, set in the casing and extending into the chamber, 91, at opposite points in its periphery, serve respectively for positioning in the chamber, 91, a rigid contact, 94, and the spring contact, 95, whose terminal buttons, 94^a and 95^a, are normally 5 in contact as seen in Figure 6, the spring contact being connected by a spacer, 97, with the center of the diaphragm, 92, so that the reaction of the spring, 93, tends to enforce the contact of the buttons, 94^a and 95^a.

15 The casing has a chamber, 98, extending up alongside the chamber, 91, to a height determined upon for adapting said chamber, 98, to act as a stand pipe for liquid communication with the chamber, 91, for exerting pressure on the diaphragm to expand said chamber, 91, and cause the diaphragm to withdraw the spacer, 97, from the spring contact, 95, and permit the latter to react for separating the buttons, 94^a and 95^a, or if the spacer 20 is attached to the spring contacts,—as it may be,—to withdraw the spring contact with the spacer, and separate the buttons, breaking the circuit. The casing, 90, as to both its 25 chambers, 91 and 98, is in communication 30 through the pipe, 11, with the discharge of the pumping device, said pipe being connected at the side of the casing, 90, through a nipple, 99, leading to a hollow boss, 99^a, which opens downwardly at the center of the circular base, 90^b, of the casing, 90, which is peripherally flanged as seen at 90^c, and shou- 35 dered as seen at 90^d, for seating on and closing the upper end of a sediment cup, 90^x, between which and the casing there is clamped 40 a strainer, 90^e, and a gasket, 90^f, the strainer being clamped at the end of the central boss, 99^a, by a T-fitting screwed into the boss and constituting the continuation of the entrance 45 passage for liquid which is thus introduced 50 below the strainer and passes up through the latter into the chamber, 98, and thence by 55 ports, 98^d, in the partition, 98^c, into the chamber, 91.

The operation of the construction shown may be understood from the foregoing description to be as follows:

55 The main fuel tank, B, being supplied with fuel submerging the pump shown in Figure 2, and the electric circuit being energized from the current source, the absence of pressure in the fuel line 11—13 permits the switch shown in Figure 6 to be closed, and the solenoid windings, 41—41 of the pump, seen in Figure 2, are accordingly alternately energized, the alternation being effected by the action of the snap switch comprising the snap lever, 51, as above described.

55 The alternate energizing of the solenoid winding produces the reciprocation of the solenoid armature-piston member, 42, for

pumping the fuel, which is forced by way of the fuel line 11—13 to the carburetor, passing through the chamber, 91, of the governing device, in which chamber the pressure of the liquid operates on the diaphragm, 92, tending 70 to expand the chamber and separate the switch contacts, 94 and 95, and effecting such separation when the pressure exceeds the resilient reaction of the spring, 93; whereupon the solenoid windings being de-energized, the 75 operation of the pump is interrupted until the decline of pressure in the fuel line permits the switch to close causing the re-energized pump to resume operation.

I claim:

1. An apparatus for supplying fuel to an internal combustion engine from a fuel source at a lower level than the engine carburetor comprising in combination with a main fuel supply source, an electrically energized pumping device mounted in position to be entirely submerged both as to the pump parts and as to the electric motor parts in the fuel at the main fuel supply source, a fuel delivery conduit leading from the pump for supplying the engine, the energizing electric circuit being extended in portions of said conduit and comprising a switch submerged in the fuel moving through said conduit.

2. In an apparatus for supplying fuel to an internal combustion engine from a fuel source at a lower level than the engine carburetor comprising in combination with a main fuel supply tank, an electrically energized pumping device mounted within said main tank in position to have its intake submerged in the fuel content of the tank; a fuel delivery conduit from the pump to the engine; a circuit in which the motor element of said pumping device is energized extended in said fuel delivery conduit; a governing switch interposed in the circuit having its cooperating circuit-making-and-breaking members submerged in the fuel passing through said conduit.

3. An apparatus for supplying fuel to an internal combustion engine from a fuel source located at a lower level than the engine carburetor comprising in combination with a main fuel supply tank, an electrically energized pumping device mounted in position to be supplied by gravity from the main tank, a fuel delivery conduit from the pump to the engine, the electric motor mechanism being embodied in the pump mechanism and the energizing circuit being extended from the pump within the fuel conduit leading from the pump, the fuel delivery conduit from the pump to the engine comprising a fuel accumulating apparatus comprising a fuel-containing chamber at a higher level than the engine carburetor, the pump motor energizing circuit being extended through said fuel accumulating apparatus, and the governing switch being arranged in con-

- nection with the same having its cooperating circuit-making-and-breaking members in said fuel-containing chamber in position to be submerged in the fuel content thereof.
5. 4. An apparatus for supplying fuel to an internal combustion engine from a fuel source at a lower level than the engine carbureter comprising in combination with a main fuel supply tank, an electrically operated pumping device located relatively to the tank for deriving fuel therefrom and forwarding it to a higher level; a fuel conduit from the pump to the engine carbureter comprising a fuel accumulating apparatus located at a higher level than the carbureter intake, the pump energizing circuit extending within the fuel conduit to said apparatus, said apparatus comprising a standpipe member and a variable capacity chamber having
- 10 liquid communication with the lower part of the standpipe member, and having a movable wall member by whose movement the chamber capacity is varied, and a governing switch in said circuit having its cooperating members positioned in said variable capacity chamber for submergence in the fuel content thereof.
5. In an electromagnetic fuel pumping apparatus for supplying the carbureter of an internal combustion engine, a pair of electro magnets and armatures for them respectively, the armatures being connected together for simultaneous movement in the direction of the magnetic attraction of the magnets respectively; a circuit in which both magnets are energized, comprising a switch arranged for shifting the circuit from the winding of one magnet to the winding of the other, and operating connections from the connected armatures for operating the switch in the direction for breaking the circuit through the winding of the magnet by whose armature the switch is thus operated; a pumping chamber and piston reciprocating therein operatively connected with the connected armatures, the pumping chamber having communication at its opposite ends for inflow and discharge of the fuel to be pumped; a hollow casing within whose cavity the structure comprising the magnets, armature, pumping chamber and piston is contained and enclosed, the communication of the opposite ends of the pumping chamber being with said casing cavity, said casing having at each end a fuel inlet and a fuel discharge port, and valves controlling said ports respectively opening for flow through the casing in one direction and seating against reverse flow.
- 30 6. In the construction defined in claim 5, the structure comprising the two magnets, armatures, pump chamber and piston, constituting a partition in the casing, dividing it into two chambers, and separating an inlet and an outlet at the other side of said partition.
7. In the construction defined in claim 5, the structure comprising the magnets, armatures, pump chamber and piston, constituting a partition in the casing dividing it into two chambers and separating an inlet and an outlet at one side from an inlet and outlet at the other side of such partition, the casing having a third chamber with which the outlet from both the separated chambers communicate, and a fuel discharge conduit from said third chamber.
8. In the construction defined in claim 5, the two magnets being mounted with their armature-attracting poles facing in opposite directions, the armatures being connected rigidly across the extent of the magnets between said oppositely facing poles, the pump chamber being located in said interval, and the pump piston being carried by connection between the armatures.
9. In the construction defined in claim 5, the magnet-controlling switch for shifting the circuit from one magnet winding to the other being located within the casing whose cavity is partitioned by the magnet and pump structure at one side of said partitioning structure, and connections extending in said partitioning structure from the side thereof opposite that at which the switch is located for operating the switch by the armature at said opposite side.
10. In a fuel feeding system for motor vehicle internal combustion engines, a source of fuel supply for the engine carbureter, and fuel pumping means associated therewith for impelling the fuel to the carbureter; electrically energized means for operating the pumping means, and a fuel-conducting pipe line from the pump to the carbureter; a pressure chamber in said pipe line, the energizing circuit of the pumping means comprising a conducting part extending from the electric pump-operating means into said pressure chamber and out of said chamber to a source of current, and comprising contacts located within the pressure chamber and insulated carrying means for the same, and means exposed to the fuel pressure in said pressure chamber and adapted to be moved thereby operatively connected with the carrying means of one of said contacts for moving the latter to separate the contacts upon the fuel pressure in said chamber reaching a predetermined degree.
11. A fuel feeding system for supplying an internal combustion engine comprising a fuel supply tank, an electrically energized pump mounted at the bottom part of the tank for submergence of its intake in the fuel content of the tank, a fuel delivery conduit leading from the discharge of the pump upwardly emerging from the upper part of the tank and continuing thence to the engine, said conduit comprising a chamber outside the tank,

the pump-energizing circuit being extended from the pump inside said conduit into said chamber, and comprising a circuit-making-and-breaking switch having both its operating contacts located in said chamber and therein arranged to be operated by the fuel pressure due to the pumping, for interrupting the circuit upon predetermined pressure in said chamber.

10 In testimony whereof, I have hereunto set my hand at Chicago, Illinois, this 29th day of November, 1929.
